United States Patent Office

Des. 219,618
Patented Dec. 29, 1970

219,618

GUITAR OR SIMILAR ARTICLE

Orbra W. Appleton, 614 S. 12th St.,
Burlington, Iowa 52601

Filed May 5, 1969, Ser. No. 17,007

Term of patent 14 years

Int. Cl. D17—03

U.S. Cl. D56—1

FIG. 1 is a plan view of a guitar or similar article embodying the design;

FIG. 2 is a side elevational view; and

FIG. 3 is an end elevational view thereof.

The back of the guitar, not shown, is unornamented. Portions of the drawing figures have been shaded to indicate contrast in appearance.

I claim:

The ornamental design for a guitar or similar article, as shown and described.
